CLAIM

The ornamental design for a connector for communication device as shown and described.

DESCRIPTION

FIG. 1 is a front, left side, top perspective view of the connector for communication device showing our new design;

FIG. 2 is a rear, right side, top perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof; and,

FIG. 8 is a right side elevational view thereof.

The dashed broken lines in the drawings depict portions of the connector for communication device that form no part of the claimed design.
